(57) **CLAIM**

The ornamental design for a hanging storage bin, as shown and described.

DESCRIPTION

FIG. 1 is a perspective view of the hanging storage bin;
FIG. 2 is a front elevational view of the hanging storage bin;
FIG. 3 is a rear elevational view of the hanging storage bin;
FIG. 4 is a side elevational view of the hanging storage bin;
FIG. 5 is a top plan view of the hanging storage bin; and,
FIG. 6 is a bottom plan view of the hanging storage bin.

The broken lines designating the mesh of the hanging storage bin are for illustrative purposes only, they are not intended to designate any particular pattern in the mesh of the hanging storage bin, and they form no part of the claimed design. The broken lines depicting hardware represent environmental elements only and form no part of the claimed design.
